UNITED STATES PATENT OFFICE.

FRANK R. CHESTER, OF NEW YORK, N. Y., ASSIGNOR TO CHESTERFIELD CONTROL COMPANY, OF DOVER, DELAWARE, A CORPORATION OF DELAWARE.

BASEBALL GAME.

Application filed April 7, 1927. Serial No. 181,687.

It is an object of the invention to provide a game by means of which certain results may be accomplished, the achievement of such results being dependent upon the 5 skill of operation of the improved game.

It is a further object of the invention to construct a device of this character which preferably will be of the baseball type, and in which the plays of the actual game, to 10 the greatest extent, may be duplicated with fidelity.

Another object of the invention is that of providing a game conveniently of the type mentioned in the preceding paragraph the 15 mechanism of which may be actuated by two operators, one having control of the "team" which is at bat, and the other having control of the "team" which is opposing the first team.

20 Still another object is that of providing a device of this type the parts of which will be relatively few in number and rugged in construction, the entire device being readily assembled to provide a mechanism which 25 may be subjected to hard usage over long periods of time with freedom from mechanical difficulty, and from the operation of which a great amount of pleasure will be derived.

30 Other objects of the invention will in part be obvious and in part will appear hereinafter.

With these and further objects in mind, the invention accordingly comprises the features of construction, combination of elements and arrangement of parts which will 35 be exemplified in the construction herein-after set forth, and the scope of the application of which will be indicated in the 40 claims.

For a fuller understanding of the nature and objects of the invention reference should be had to the following detailed description taken in connection with the accompanying 45 drawing, in which:

Figure 1 is a plan view of one form of game embodying the improved construction of the present invention;

Fig. 2 is a sectional side view thereof;

Fig. 3 is a sectional plan view;

Fig. 4 is a longitudinal section taken from the rear of the plane of Fig. 2;

Fig. 5 is a fragmentary enlarged sectional view of a detail of the mechanism as shown in Fig. 4 and as viewed from the reverse 55 side;

Fig. 6 is an enlarged fragmentary elevation of the missile-impelling member;

Fig. 7 is a fragmentary sectional plan view taken along the lines 7—7 and in the 60 direction of the arrows of Fig. 2;

Fig. 8 is a view similar to Fig. 1, but showing a slightly different form of mechanism from that used in the former figure; and

Fig. 9 is a sectional side view of the mechanism of Fig. 8. 65

In these views the numeral 5 indicates the deck of the machine, which is formed with an opening below which is movably mounted a plate 6. The face of the deck is arranged 70 to simulate the appearance of a baseball field, and the deck is formed with a slot 7 laid out to correspond to the base lines of a diamond.

At this time it will be observed that the deck plate portions preferably are mounted 75 within a cabinet embracing a base 8 and side walls 9 and that the surface of the entire deck plate and deck proper preferably are inclined toward a common point, as has been shown in Figs. 2 and 4. Likewise, it 80 will be noted that the base of the cabinet, or the surface of a member 10 (indicated in dotted lines) positioned above the same, is inclined toward a common point so that a missile upon the surface will gravitate to 85 this point, at which there is arranged a missile-receiving and elevating mechanism, indicated diagrammatically at 11, and by means of which a missile may be transferred from the surface 10 to the upper surface of 90 the deck upon which it will move of its own initiative until it reaches a position of rest at the most depressed portion of the deck, in the present instance, at a position centrally within the diamond and at a location 95 approximating that of the pitcher's box. At this most depressed point the deck is formed with a slot 12 through which an arm 13 extends, this arm acting as a missile-impelling member and being directed to act 100 toward a bat 14 conveniently including, as in Fig. 1, a heart-shaped body.

The slot 7 serves as a track for an element 15 preferably simulating in appearance a

figure of a runner, and this figure is moved in a manner hereinafter described to traverse the entire length of the slot beginning with the position of home plate and returning to such position. It will be noted that the deck plate is formed with missile-receiving portions, in the present instance openings 16 corresponding in number and location to the position of field players, and an 10 opening is provided in the infield portion and approximating the location of the pitcher, this opening being closed by a pivotally-connected trap-door 17.

In a game of this nature it is preferred 15 that two players actuate the game mechanism in opposition to each other. To this end, in the present instance a pair of shafts 18 and 19 extend transversely of the cabinet body and beyond the same, at which point 20 they mount hand wheels 20 by means of which they may be rotated. The shaft 18 provides a worm-portion 21 meshing with a worm-wheel 22 secured to a collar 23, which latter extends vertically at a point preferably 25 equidistant between the bases and is disposed wholly below the deck. Secured to the collar 23 and driven by the worm-wheel is a disk 24 having cam-portions 25 in its periphery and located 90° apart. A 30 spring-pressed rod 26 is slidably mounted on the under face of the plate 6 and is provided with a roller 27 at its inner end which bears against the periphery of the disk 24, the spring urging this roller to a position at 35 which it rests within the base of the depressions or cam-portions 25 when the latter are in line therewith. The rod 26 carries, for example bars 28 and 29 and a plate 29', which underlie the openings 16 when the 40 rod 26 is in the position shown in Fig. 3, but, upon the rod being retracted by engagement of the roller 27 with the outermost peripheral portions of the disk 6, these openings will be uncovered so that a missile may 45 drop therethrough onto the surface 10.

At this time it will be noted that the collar 23 is mounted upon a sleeve 30, which is formed with slots adjacent its upper and lower ends and within which there is disposed a second sleeve 31, and that, in turn, within the latter there are disposed push-rods—in the present instance, in the nature of split sleeves 32 and 33. The rod 34 has one of its ends secured to the bar 26, its opposite end being attached to the lower arm of a bell-crank lever 35, the second arm of which has a pin-and-slot connection with the sleeve 32. This structure has been indicated in dotted lines in Figure 3 and a 55 substantial duplicate thereof is shown in full lines at 67, 68 and 69 in Figure 2, and which latter structure will be hereinafter more fully described. As shown in Fig. 5, the upper end of this push-rod or sleeve has 60 connection with the pivotally-mounted trap-

door 17 so that, as the bar 26 is moved rearwardly to uncover the several openings of the deck, the rod 34 likewise will move, rocking the bell-crank lever 35, moving the sleeve 32 downwardly, thus moving the trap-door 17. 70

In line with one of the depressions or cam-portions 25 of the disk and secured to the body 24 of the latter is a bracket 36, upon which a post 37 is slidably mounted, this 75 post mounting the figure 15. As a consequence, it will be understood that with the figure of the runner adjacent any of the bases all openings of the infield and outfield will be covered against the passage of 80 a missile therethrough, while, if the runner is away from any one of such bases, these openings will be uncovered, for the reason that the bracket and figure carried thereby are so disposed with respect to the cam-portions 25 of the disk that as the figure 15 reaches a position of safety, i. e., adjacent each base, the bar 26 is projected to cover these openings. 85

As shown, the shaft 18 is split, the parts 90 thereof being coupled by a friction clutch 38, so that while movement of the hand wheel will turn the shaft, the parts to be driven thereby may not be injured, for the reason that if the mechanism should jam a 95 continued turning of the hand wheel will result merely in the clutch parts slipping with respect to each other.

At this time it will be observed that the bat 14 is mounted upon the vertically-extending shaft portion of a crank 39, and that the outstanding arm of this crank is connected by a link 40 to the upper end of the sleeve 31. The lower end of this sleeve is connected by a rod 41 to a cam 42 secured 100 to the shaft 18, this rod acting as a follower for the cam, so that as the shaft is rotated the rod will be oscillated to simultaneously move the sleeve 31, thus moving the link 40 and oscillating the bat 14 to present different angular faces to the missile impelled 105 by the actuating member 13. 110

It is preferred that some provision be made for returning the shaft 18 under some circumstances to its initial position. To 115 this end, a gear 43 may be secured to this shaft and drive a gear 44 secured to an adjacent stub-shaft. A drum 45 is attached to this stub-shaft, and this drum and the gear 44 carry cooperating clutch parts which are 120 normally engaged incident to the action of a spring-pressed throw-rod 46. Link-connected to the outer end of this throw-rod is a pawl member or actuating lever 47, which is arranged in a plane at which it may 125 operate with a portion of the bracket 36 or parts associated therewith, so that each time this bracket moves past the station of the lever or pawl 47 it actuates the throw-rod 46 to release the clutch parts and permit ro- 130

tation of the drum 45 with respect to the gear 44. Secured to the drum 45 is one end of a cord or chain 48, the opposite end of which carries a weight 49, the position of which, when the parts are in their initial stations, will be immediately above the surface of the member 10 or the base 8. When an operator rotates the shaft 18 the weight will be drawn upwardly, and if the shaft is released at any point in advance of the "home" position of the figure 15, the parts will be returned to their initial position by the action of the weight. However, if the run is completed the bracket or parts associated therewith will cause the clutch parts of the drum-gear to be released, so that the weight returns to its initial position; and upon further movement of the shaft 18 in the same direction these clutch parts again engage to repeat the foregoing operation.

The plate 6 being shiftable with respect to the fixed deck-portion, the missile-receiving openings also will be shiftable. While this shifting may occur in any desired manner, it is preferred to accomplish the same by securing a bevel gear 50 to the inner end of a shaft 51, which gear drives a gear 52 and a crank 53 secured thereto, the end of the latter riding within a guide 54 secured to the under face of the plate 6 and, as a consequence, these parts will serve to oscillate this plate with respect to the fixed field portion as the shaft is rotated. While the shaft 51 may form a continuation of the shaft 19, it is preferred, as shown, that the former be in the nature of a countershaft; the two shafts being coupled by a reduction gearing 55, which serves to effect one rotation of the shaft 51 as the hand wheel 20 associated with the shaft 19 is rotated twice. The shaft 51 has a crank-portion 56 with which a crank 57 is connected, and, as shown, the crank is secured to a bar 58 mounted to move between guides 59, the bar carrying a trigger mechanism 60 automatically coupling and releasing the bar from a second bar 61, also mounted within the guideways 59. At one end of the base a lever 62 is rockingly mounted, and the end of this lever is link-connected as at 63 to the bar 61, a spring 64 being interposed between these elements. The lever 62 is connected by a shaft 65 to a lever 66 to oscillate the latter, and this lever is link-connected as at 67 to the lower arm of a bell-crank 68, which, similarly to the crank 35, has a pin-and-slot connection 69 with the push-rod provided by the sleeve 33. As in Fig. 6, the upper end of the rod or sleeve 33 has a pin-and-slot connection 70 with an arm 71 secured to the impelling member 13 so that as the sleeve 33 is moved the impelling member will be moved accordingly.

Thus, as the shafts 19 and 51 are rotated, the plate providing the field will be oscil-

lated, and the spring 64 will be periodically compressed, and upon the automatic release of the trigger mechanism this spring will cause the arm 13 to snap forwardly, impelling any missile arranged in advance of the same toward the bat 14; the trigger mechanism automatically coupling the bars to each other during each cycle of operation.

In operation, the missile-delivering mechanism will be actuated by a coin-controlled member (not shown) or otherwise, in order to position the missile 72 upon the upper face of the deck, over which it will roll of its own initiative until it comes to rest in advance of the impelling member 13. If each of the two operators grasps one of the hand wheels 20, the first operator (actuating the shafts 19—51) will effect first a periodic snapping of the impelling member to project a missile toward the bat 14, and second, this actuation of the shafts will cause the oscillation of the field plate 6. The operator actuating the shaft 18, by rotating his hand wheel, will oscillate first the bat 14 so that the direction of rebound of the missile may be controlled; secondly, he will cause the "runner" figure 15 to traverse the base line, and in so doing the missile-receiving openings of the infield and outfield will be uncovered during the time the "runner" figure is between the bases; thirdly, this operator will actuate the mechanism by means of which the parts are returned to normal position after an "out" is accomplished.

Thus, the playing of the game depends upon skill of operation, for the reason that the actuation of the impelling member may be gauged by one operator to project the missile at an inopportune moment toward the bat. Furthermore, upon the rebound of the missile this operator, by his skill of operation, may bring one of the openings of the movable plate into line with the path of travel of the missile over the deck. Conversely, the skill of the second operator determines the manner of rebound of the missile, and also determines whether the missile-receiving openings will be uncovered when the missile reaches a position at which it might pass therethrough.

In the event that the missile does pass through one of these openings, it is obvious that it will drop into the body of the cabinet and gravitate along the surface and enter the elevating and delivering mechanism, the entire cycle of operation being thereupon repeated. The same is true of a game of the structure shown in Figs. 8 and 9. The results aforescribed are achieved in the mechanism of Figs. 8 and 9, as follows: The runner 15 is carried by the link of a sprocket chain 73 mounted upon sprockets 74 to underlie the track provided by the slot 7. Secured to the collar 23 is a gear 75 which

meshes with a sprocket 76 having a hub, the upper end of which terminates in a sprocket 77, the diameter of which is slightly larger than the sprocket 76. The sprocket 77 meshes with the links of the chain 73 so that as the collar is rotated the figure 15 moves in unison with the cam or actuating member 24. An extension 78 may be carried by the link of the chain adjacent which the runner figure is mounted, and this extension 10 serves for cooperation with the outer end of the lever 47 in order to actuate the clutch mechanism described in connection with the preceding figures.

15 The mechanism for impelling the missile 72, as shown, may include a sleeve 79 within which a plunger 80 is slidably mounted, the plunger preferably being of such length and having such a field of travel that when extended to either of its limits of motion it projects materially beyond the ends of the sleeve 79. Consequently, if the missile 72 should come to rest against the rear end of the sleeve 79 it may be shifted from its position 20 so that it will gravitate to the lowest point of the field or deck.

25 In this connection it is to be noted that in the embodiment under consideration the lowest point of the game surface is provided by a plate 81 arranged directly in advance of the missile-impelling member; this plate being hingedly mounted and link-connected as at 82 to the actuating rod 26 so that, as aforescribed, when the latter is moved 30 to uncover the openings in the plate 6 the opening in advance of the missile-impelling member likewise will be simultaneously exposed.

35 With final reference to these figures it will be observed that the plunger 80 is connected by a lever 83 to a link 84, which latter is connected to a lever 85 normally urged rearwardly by a spring 86, the end of this lever preferably being rounded as at 87 and 40 extending in the path of travel of a cam 88 secured to the shaft 51. As a consequence, as the latter is revolved in a clockwise direction, the lever will have its upper end rocked forwardly against the tendency of the 45 spring 86, and upon the cam clearing the rounded portion 87 this lever will be snapped rearwardly, thus rapidly moving the link 84 and projecting the plunger 80 with sufficient speed to accurately impel the 50 missile toward the bat.

55 Thus, among others, the objects of this invention have been accomplished, and since certain changes may be made in the above construction, and different embodiments of 60 the invention could be made, without departing from the scope thereof, it is intended that all matter contained in the above description or shown in the accompanying drawings shall be interpreted as illustrative 65 and not in a limiting sense.

It is also to be understood that the following claims are intended to cover all of the generic and specific features of the invention herein described, and all statements of the scope of the invention which as a matter 70 of language might be said to fall therebetween.

Having described my invention, what I claim as new and desire to secure by Letters Patent is:

75 1. A game, including a deck having its surface inclined toward a common point, a missile-impelling member located adjacent such point, a missile to be disposed upon said deck, a target member movably disposed upon said deck and means for shifting said target member.

80 2. A game, including a deck having its surface inclined toward a common point, a missile-impelling member located adjacent such point, and a bat toward which the missile impelled by said member travels.

85 3. A game, including a deck having its surface inclined toward a common point, a missile-impelling member located adjacent such point, and a bat presenting angular surface toward which the missile impelled by said member travels.

90 4. A game, including an inclined deck, a missile-impelling member upon said deck adjacent the lowermost point thereof, a bat comprising a cam-shaped member arranged upon said deck and in the path of travel of an impelled missile, and means for shifting the bat.

95 5. A game, including a deck, a missile-impelling member upon said deck, a bat arranged upon said deck and in the path of travel of an impelled missile and presenting surfaces extending at angles to each other, and means for shifting said bat to present different surfaces to the impelled missile.

100 6. A game, including a deck provided with missile-receiving portions, a missile to travel over said deck, and means for shifting said portions with respect to said deck to intercept the missile.

105 7. A game, including a deck provided with missile-receiving openings, a missile to travel over said deck, and means for shifting areas of the deck within which said openings are formed to intercept the missile in its travel over said deck.

110 8. A game, including a deck having a fixed portion and a movable portion, the latter being formed with an opening, a missile to travel over said deck, and means for shifting the movable deck portion to bring the opening therein to intercept the path of travel of said missile thereover.

115 120 9. A game, including a deck comprising a fixed plate and a movable plate, the latter being formed with missile-receiving portions, a missile to travel over said deck, and means for shifting the movable plate to 125 130

- bring the missile-receiving portions to a point at which one of them intercepts the missile in its travel over said deck.
10. A game, including a deck having missile-receiving portions, a missile to travel over said deck, and means operating to render said missile-receiving portions inoperative during certain stages of actuation of the game.
11. A game, including a deck formed with a series of missile-receiving openings, a missile to travel over said deck, and means acting during certain stages of operation of the game to close said openings to prevent the passage of a missile therethrough.
12. A game, including, in combination, a deck having missile-receiving portions, a missile-impelling member, and means for actuating said member to impel a missile over said deck and to bring said portions to positions at which the missile, in its travel over said deck, is intercepted.
13. A game, including, in combination, a deck having a shiftable portion formed with a missile-receiving opening, a missile-impelling member, and means for actuating said member to impel a missile over said deck and to shift the movable portion of the latter to bring the opening therein to a position at which it intercepts a missile in its travel over said deck.
14. A game, including, in combination, a deck over which a missile is to move, a missile bat upon said deck, a member movable with respect to said deck and independent of said bat, said member representing a player, and common means for shifting said bat and moving said member.
15. A game, including a deck formed with means defining a baseball diamond, a member movable along the base lines of said diamond and representing a runner, a bat at the apex of said diamond and independent of said member, a missile to be impelled toward said bat and to rebound therefrom, and a single means for shifting the position of said bat and causing said member to move with respect to said deck.
16. A game, including, in combination, a deck comprising fixed and shiftable parts, the latter having a missile-receiving portion, a bat associated with said deck, means also associated with said deck and defining a baseball diamond, a member movable with respect to said deck and along the base lines of said diamond and representing a runner, a member for impelling a missile toward said bat, means for actuating said impelling member and shifting the movable deck-portion to bring missile-receiving portions of the latter to a point at which they intercept a missile traveling over said deck, and means for shifting said bat and moving said member along the base lines.
17. A game, including, in combination, a deck comprising fixed and shiftable parts, the latter having a missile-receiving portion, a bat associated with said deck and defining a baseball diamond, a member movable with respect to said deck and along the base lines of said diamond and representing a runner, a member for impelling a missile toward said bat, means for actuating said impelling member and shifting the movable deck-portion to bring missile-receiving portions of the latter to a point at which they intercept a missile traveling over said deck, mechanism for rendering the missile-receiving portions inoperative, and means for shifting said bat and moving the member along the base lines and actuating said mechanism when said member reaches certain positions.
18. A game, including a deck comprising fixed and movable portions, the latter having a missile-receiving opening, a member for impelling a missile over said deck, a bat associated with said deck and in the path of travel of the missile impelled by said latter member, and said deck having thereon means defining a base line, a member shiftable along said base line, mechanism for closing the opening in the movable portion of the deck when said last-named member reaches certain positions along said base line, means for actuating the missile-impelling member and shifting the movable deck portion to bring the opening therein to a position at which it intercepts the missile traveling over said deck, and means for shifting said bat and moving the member along the base line.
19. A game, including a deck formed with means defining a baseball diamond, a missile-impelling member upon said deck, a bat-member adjacent the apex of such diamond and in the path of travel of missiles impelled by said member, said deck being formed with a shiftable missile-receiving portion, means for controlling said bat and the shifting of such portion, and means for controlling the actuation of said impelling member.
20. A game including a deck formed with an opening, a player member movable with respect to said deck, a game simulating representation upon said deck, means for obstructing said opening to prevent the passage of a missile from said deck therethrough and means for shifting automatically said obstructing means to inoperative position when said member is shifted to a point away from a predetermined area of said game representation.
21. A game of the baseball type including a deck inclined towards a common point, a missile-impelling means located adjacent such point, a missile, said deck being formed

with an opening through which said missile passes, a bat disposed upon said deck and movable with respect to the same for projecting a missile impelled towards the same by said means, means for operating said bat and means for actuating said impelling means.

22. A game of the baseball type including a deck formed with openings and having a representation of a baseball diamond, means for pitching a missile across said deck, means for batting such pitched missile, said missile passing from said bat towards said openings, means representing a runner traversing said diamond, means whereby an "out" may be registered only when said runner-representing means is disposed at a point remote from one of the bases of said diamond and

means for operating said impelling, batting and runner-representing means. 20

23. A game of the baseball type including a deck having thereon the representation of a baseball diamond including base portions, a missile, means for impelling said missile across said deck, means for batting said impelled missile, means representing a runner traversing the base lines of said diamond, means whereby an "out" of the batted missile may be achieved and means for rendering said last-named means inoperative 25 when said runner-representing means is adjacent any of the base positions of said diamond. 30

In testimony whereof I affix my signature.

FRANK R. CHESTER.
